UNITED STATES PATENT OFFICE

94,420

DESIGN FOR A BATHING SUIT

Milton E. Hayman, West Hartford, Conn.

Application June 12, 1934, Serial No. 52,148

Term of patent 3½ years

To all whom it may concern:

Be it known that I, Milton E. Hayman, a citizen of the United States, residing at West Hartford, in the county of Hartford and State of Connecticut, have invented a new, original, and ornamental Design for a Bathing Suit, of which the following is a specification, reference being had to the accompanying drawing forming a part thereof.

In the drawing:

Fig. 1 is a rear view of the bathing suit as it would appear when being worn; Fig. 2 is a corresponding front view; and Fig. 3 is a front view of the suit as it would appear on a counter for sale.

The garment forming the invention comprises a bathing suit of closely woven or knitted fabric associated with an open mesh fabric in the fanciful arrangement shown in the drawing annexed hereto.

I claim:

The ornamental design for a bathing suit, as shown and described.

In testimony whereof, I hereto affix my signature.

MILTON E. HAYMAN.
